UNITED STATES PATENT OFFICE.

ERNEST A. LE SUEUR, OF OTTAWA, CANADA.

PROCESS OF TREATING ACETYLENE FOR FACILITATING ITS TRANSPORTATION AND STORAGE.

SPECIFICATION forming part of Letters Patent No. 781,009, dated January 31, 1905.

Application filed June 11, 1904. Serial No. 212,124.

To all whom it may concern:

Be it known that I, ERNEST A. LE SUEUR, a subject of the King of Great Britain, residing at Ottawa, in the county of Carleton and Province of Ontario, Canada, have invented new and useful Improvements in the Art of Treating Acetylene to Facilitate Its Transportation, Storage, and Use, of which the following is a specification.

10 My invention aims to overcome the difficulties hitherto found to be associated with the transportation and distribution of condensed acetylene.

Under the high pressures ordinarily associated with liquid acetylene the latter has been found liable to explosion from whatever cause. When acetylene gas is compressed into steel tanks, the weight of the latter has been found an insuperable commercial drawback to their 20 distribution. When condensed to the solid or liquid form at low pressures by refrigeration of high intensity and protected from avoidable access of heat by lagging, acetylene tends to volatilize too rapidly in proportion 25 to its total mass, except where the latter is large by comparison, for instance, with what would be needed to supply a household.

My invention presents a method whereby advantage for purposes of transportation and 30 distribution of acetylene may be taken of the facts, on the one hand, of the many hundred-fold reduction in its volume when condensed by refrigeration and, on the other, of its natural condensation of volume under compression, and whereby the disadvantages above mentioned of these two methods are eliminated.

My process consists in condensing the acetylene to the form of a solid or liquid or of a 40 mixture of the two at a very low temperature (around 100° Fahrenheit below zero) at atmospheric or other comparatively low pressure, in transporting it as desired in a vessel of small size and weight in the refrigerated 45 condition, then in placing the interior of said vessel in communication with that of a stationary receiver of which the capacity and strength are sufficient to accommodate the gas volatilized from the refrigerated condensed 50 acetylene contained in said vessel, and in leav-

ing matters in this condition until the said refrigerated acetylene has volatilized. The said receiver (from which such acetylene as is thereafter required for use is withdrawn as desired) thus becomes a stationary storage-tank for 55 any acetylene volatilized over and above what may be needed for use prior to the complete evaporation of the refrigerated acetylene. The difficulty with regard to the wasting of the refrigerated charge is thus eliminated at 60 the same time that that pertaining to the carriage of compressed acetylene in enormously cumbersome tanks is avoided. The need for such an improvement lies in the fact that acetylene alone among gases can explode with 65 great violence when maintained in the liquid condition under the excessively-high pressure associated with liquid acetylene at ordinary temperatures.

I may point out that any method of increasing the virtual capacity of the above-mentioned receiver by placing an absorbent in it or of permitting the use of a more easily attained low temperature for the condensing of the gas in the first place by the same means 70 may, if desired, be made use of in connection with my process—that is to say, I may transport a refrigerated mixture, say, of acetone and acetylene (which on absorption of heat of low potential gives off substantially acetylene) 75 and deliver it (or the volatilized portion) to a stationary tank, which may itself contain a solvent or other absorbent. However, the great advantage of sending acetylene out in the solid condition will usually make the use 80 of a solvent during carriage unnecessary and undesirable.

A variation of the process described may be employed as follows: Instead of simply connecting the interiors of the transporting vessel and the storage-receiver I may immediately deliver the refrigerated condensed acetylene from the cold transporting vessel to the comparatively warm stationary receiver.

I claim—

1. The process of effecting transportation and storage of acetylene which consists in condensing it, at atmospheric or other comparatively low pressure, to the liquid or solid form by refrigeration, in transporting it in the re- 95 100

frigerated condition and then admitting it to a storage-receiver, of many times the volume of the refrigerated acetylene, possessing a comparatively high temperature, substantially as and for the purposes set forth.

2. The process of effecting transportation and storage of acetylene which consists in condensing it, at atmospheric or other comparatively low pressure, to the liquid or solid form 10 by refrigeration, in transporting it in the refrigerated condition in a suitable vessel and thereafter in allowing it to expand, under pressure higher than that of the atmosphere, to the gaseous condition, into a storage-receiver possessing a comparatively high temperature, substantially as and for the purposes described.

3. The process of effecting transportation and subsequent storage of acetylene which 20 consists in condensing it, at atmospheric or other comparatively low pressure, into solution in a solvent by refrigeration, in transporting the solution in a refrigerated condition and then in admitting it, or the gas which

boils off therefrom, to a storage-receiver possessing a comparatively high temperature, substantially as and for the purposes set forth.

4. The process of effecting transportation and storage of acetylene which consists in condensing it, under a comparatively low pressure, by refrigeration, in transporting it in the refrigerated condition and then in admitting it to a storage-receiver containing a liquid or solid absorbent for acetylene.

5. Improved process of effecting distribution of acetylene which consists in preparing it in the liquid or solid form at a selected low pressure by the aid of refrigeration; in transporting it in a refrigerated condition in suitable vessels and then in effecting storage at 30 comparatively high temperatures in stationary vessels of great volume compared to that of the transporting vessels, substantially as and for the purposes set forth.

ERNEST A. LE SUEUR.

In presence of—

MAUD S. LE SUEUR,
H. B. LE SUEUR.
